(57) **CLAIM**

The ornamental design for an indicator, as shown and described.

DESCRIPTION

The patent of application filed contains at least one drawing executed in color. Copies of this patent of patent application publication with colored drawing(s) will be provided by the Office upon request and payment of the Office upon request and payment of the necessary fee.

FIG. 1 is a front view of my new indicator design showing color aspects of the design wherein the trademark "sylvac" and the designation "swiss made" do not form a part of the design;

FIG. 2 is a left side view thereof;

FIG. 3 is a right side view thereof;

FIG. 4 is a top respective view thereof;

FIG. 5 is a bottom perspective view thereof;

FIG. 6 is a rear view thereof; and,

FIG. 7 is a right side perspective view thereof.
